UNITED STATES PATENT OFFICE

WILLIAM T. WALKER AND HENRY F. ORR, OF TOLEDO, OHIO

DESIGN FOR A COMBINATION BOTTLE OPENER AND BEVERAGE SPOON

Application filed July 25, 1932. Serial No. 44,444. Term of patent 7 years.

To all whom it may concern:

Be it known that we, WILLIAM T. WALKER and HENRY F. ORR, citizens of the United States, and residents of the city of Toledo, county of Lucas, and State of Ohio, have invented a new, original, and ornamental Design for a Combination Bottle Opener and Beverage Spoon, of which the following is a specification, reference being had to the accompanying drawing, forming a part thereof.

In the drawing,

Figure 1 is a plan view of a combination bottle opener and beverage spoon, showing my new design;

Figure 2 is a side elevation of the spoon shown in Figure 1; and

Figure 3 is a plan view of the underside of the spoon shown in Figure 1.

We claim:

The ornamental design for a combination bottle opener and beverage spoon, as shown.

In testimony whereof we have hereunto signed our names to this specification.

WILLIAM T. WALKER.
HENRY F. ORR.
